United States Patent Office

Des. 218,991
Patented Oct. 20, 1970

218,991

IMPRINTER

Davies Allport, La Jolla, Calif., assignor to Cubic Corporation, San Diego, Calif., a corporation of California

Filed Nov. 17, 1969, Ser. No. 20,129

Term of patent 14 years

Int. Cl. D18—02

U.S. Cl. D64—11

FIG. 1 is a perspective view of the imprinter embodying my new design;

FIG. 2 is a left side elevational view;

FIG. 3 is a right side elevational view;

FIG. 4 is a rear elevational view; and

FIG. 5 is a front elevational view.

I claim:

The ornamental design for an imprinter, substantially as shown.
